EXPLODING SPLITTING TOOL

Robert B. Hutchison, Pittsburgh, Pa.; Ella J. Hutchison and Mary W. Hutchison, executors of said Robert B. Hutchison, deceased

Application October 21, 1936, Serial No. 106,781

3 Claims. (Cl. 102—6)

This invention relates to splitting tools, and more particularly to those adapted to split an object by means of the force of an explosion occurring within the tool.

5 This invention is directed to improvements upon my splitting tool, or exploding wedge, disclosed in my Patent No. 1,882,617. That patent discloses a tool comprising a powder-receiving barrel closed at one end and provided with 10 a fuse-receiving port, and a wedge having a tubular neck secured in the open end of the barrel and provided with a transverse opening communicating with the outer end of the neck. The wedge is driven into an object to be split, such 15 as a log or block of stone, and the powder within the barrel is then exploded by means of the fuse. The force of the explosion is transmitted through the tubular neck of the wedge to its transverse opening and thereby splits the object.

20 Although this tool has been favorably received by the trade and is widely used, I have improved it in such a manner as to increase its life and efficiency. There is a tendency for 25 the wedge shown in my patent to be blown out of the object being split by the force of the explosion, whereby some of the force of the explosion is lost. Also, after an extended period of use the barrel sometimes separates from the 30 wedge member, the outer end of the neck wears away, and the fuse-receiving port becomes corroded and enlarged to an undesirable extent.

It is among the objects of this invention to provide a splitting tool which is exceedingly strong and durable, highly efficient, very resistant 35 to being dislodged from the object being split at the time of explosion, and in which corrosion of the fuse-receiving port is retarded materially.

40 According to this invention, the sides of the wedge of an exploding splitting tool are provided with projections which hold the wedge in the object being split at the time of explosion. To eliminate the danger of the barrel being blown away from the wedge, especially due to the wedge being substantially unable to leave the object being split at the time of the explosion, and to strengthen the wedge neck which extends into the barrel, the projecting portion of the neck is 45 provided with a lateral projection, preferably annular, which is enclosed or gripped by the weld that connects the neck to the adjoining end of the barrel. This projection is of such shape as to form a notch between itself and the end 50 of the barrel so that the weld can extend in-

wardly to the neck. The joint thus formed is such stronger than one in which the weld engages a smooth surface neck, and the neck is likewise reinforced. As the life of the tool is thus increased, it is desirable to prolong the useful life of the fuse-receiving port. This is done by inserting in the port a detachable plug provided with an axial bore for receiving the fuse. In case the port is eventually enlarged by corrosion, the plug can be replaced by one of slightly larger size by retapping the wall of the port. The inner end of the plug's bore is preferably restricted so that the tool can be used a long time before the plug becomes worn enough to require replacement. Likewise, the life of the neck is increased, without thickening the body of the wedge, by forming a hump on both sides of the wedge at its inner end adjoining the bore through the neck so that the wall of the bore is maintained of uniform thickness throughout its 20 length.

The preferred embodiment of the invention is illustrated in the accompanying drawing in which Fig. 1 is an elevation of my splitting tool; and Fig. 2 is a longitudinal section thereof taken 25 on the line II—II of Fig. 1.

Referring to the drawing, an elongate barrel member 1 of high grade steel is closed at one end to provide a powder-receiving chamber 2. Inserted in the open end of this chamber and 30 shrunk-fit therein is a tubular neck 3 of a metal member, preferably a wedge 4, adapted to be driven into an object to be split, such as a log or a block of stone. The neck of the wedge is securely connected to the adjoining end of the 35 barrel by a weld 6. The wedge is provided with a transverse opening 7 communicating at its inner end with the outer end of the axial bore 8 of the neck so that the force of the explosion of powder within the barrel is transmitted 40 through bore 8 and the transverse opening in the wedge to the portions of the object engaging the sides of the wedge, whereby the object is split. The taper of the wedge is slight so that the wedge will enter the object without cracking it, which would produce a cleft through which the force of the explosion might be dissipated.

It is a feature of this invention that the likelihood of the wedge being blown out of the object 50 being split is greatly diminished or entirely eliminated by providing the opposite sides of the wedge with projections which sink into the walls of the opening made in the object by the wedge. These projections are preferably in the 55

form of bosses 11 integral with the wedge, and themselves wedge-shape or tapered toward the end of the wedge so that they will not interfere with entrance of the wedge into the object to be split. They may be staggered, as shown in Fig. 1, to increase their holding power.

Due to the fact that the wedge is held securely in the object by these bosses at the time of explosion, the explosion exerts a tremendous force on the barrel outwardly relative to the wedge which may tend to separate the two after the tool has been in use for some time. To prevent separation from occurring, the portion of the neck projecting from the barrel is provided with an integral projection, preferably a ring 12 substantially semi-circular in cross section, which is enclosed by weld 6 that joins the neck to the end of the barrel. As shown in Fig. 2, the base of the ring engages the end of the barrel and thereby provides a notch or recess encircling the neck so that the weld can extend inwardly to the neck and engage the entire end of the barrel and the entire surface of the ring. Consequently, the neck is actually keyed into the weld, whereby an extremely strong connection is provided that prevents the wedge and barrel from pulling apart. Also, the neck is reinforced by the ring and weld against lateral strains encountered when the tool is being driven into an object.

The charge of powder in the barrel is set off by means of a fuse 13 inserted in a port 14 in the barrel wall. After prolonged use the repeated explosions within the barrel would corrode the wall of the port and enlarge the port so much that it would not hold the fuse. To remedy this situation a plug 16 is threaded in the port. This plug is provided with an axial bore 17 for receiving one end of the fuse, and in case the wall of the port becomes corroded, the plug can be replaced by a larger one by retapping the port wall. However, the inner end of the plug bore is preferably materially restricted, as shown in Fig. 2, so that it will require a long time for the plug to corrode and wear away to an extent such that the wall of the port is affected. Although the fuse does not extend entirely through the plug, the fire from the fuse passes through the restricted portion of bore 17 and ignites the powder.

The explosions exert a tremendous outward force on the wall of the bore through the neck of the wedge, and it is therefore highly desirable that the wall of the bore be thick enough throughout its length to resist this force. However, if the wedge is made thick enough at its inner end to provide sufficient wall thickness for the outer end of the bore wall, the wedge will be apt to crack the object into which it is driven and thereby let the force of the explosion be lost through the crack. Therefore, the thickness and taper of the wedge is such that it will not crack the object, but the outer end portion of the wall of bore 8 is maintained as thick as the remainder of that wall by forming a hump 18 on each side of the wedge adjoining the bore. These humps work into the object to be split without cracking it.

An exploding splitting tool of the foregoing construction is highly efficient because it is held in the object being split at the time of explosion, thereby directing substantially all of the force of the explosion into the object. Nevertheless,

in spite of the great force to which the tool is subjected at each explosion, it has a long and useful life due to the keyed weld connection between the wedge and barrel and to the replaceable fuse-receiving plug with the restricted bore. 5

According to the provisions of the patent statutes, I have explained the principle and construction of my invention and have illustrated and described what I now consider to represent its best embodiment. However, I desire to have 10 it understood that, within the scope of the appended claims, the invention may be practiced otherwise than as specifically illustrated and described.

I claim:

1. A splitting tool comprising an explosive-receiving barrel closed at one end and provided with a fuse-receiving port, a member adapted to be driven into an object to be split and having a tubular neck a portion of which telescopes 20 snugly within the open end of the barrel, the wall of the barrel at said open end being substantially perpendicular to the axis of the barrel, the projecting portion of said neck being provided with an integral annular projection forming with 25 the end wall of the barrel an annular substantially V-shape notch, and a weld in said notch connecting said projecting portion to the adjoining end wall of the barrel and enclosing said annular projection, said member being provided 30 with a transverse opening communicating with the outer end of said tubular neck, and the sides of said member being provided with projections.

2. A splitting tool comprising an explosive-receiving barrel closed at one end and provided with a fuse-receiving port, a member adapted to be driven into an object to be split and having a tubular neck a portion of which telescopes snugly within the open end of the barrel, the wall of the barrel at said open end being substantially perpendicular to the axis of the barrel, the projecting portion of said neck being provided with an integral annular projection with its greatest width at its base and forming with the end wall of the barrel an annular substantially 45 V-shape notch, and a weld in said notch connecting said projecting portion of the neck to the adjoining end wall of the barrel and engaging substantially the entire surface of said annular projection, said member being provided 50 with a transverse opening communicating with the outer end of said tubular neck.

3. A splitting tool comprising an explosive-receiving barrel closed at one end and provided with a fuse-receiving port, a plug detachably 55 secured in said port and provided with an axial bore for receiving a fuse, the inner end of said bore being restricted, a member adapted to be driven into an object to be split and having a tubular neck a portion of which telescopes snugly within the open end of the barrel, the projecting portion of said neck being provided with an annular projection forming with the end wall of the barrel an annular substantially V-shape notch, and a weld in said notch connecting said 65 projecting portion to the adjoining end wall of the barrel and enclosing said projection, said member being provided with a transverse opening communicating with the outer end of said tubular neck, and the sides of said member being provided with projections.

ROBERT B. HUTCHISON.
